GAS-STOVE.

1,121,691.

Specification of Letters Patent.

Patented Dec. 22, 1914.

Application filed August 17, 1911. Serial No. 644,623.

To all whom it may concern:

Be it known that I, JOHN M. TOBIAS, residing at No. 4043 Windsor street, Pittsburgh, in the county of Allegheny and State of Pennsylvania, have invented certain new and useful Improvements in Gas-Stoves, of which the following is a specification.

The primary object of this invention is to provide an efficient portable gas-stove of such construction that substantially perfect combustion is obtained, rendering a flue connection unnecessary. While non-flue stoves have been proposed, imperfect combustion has been usually encountered, rendering such stoves more or less unsafe on account of products discharged into the room being heated.

With a stove of the construction herein proposed, the products are baffled and superheated to such an extent that practically all are consumed. Furthermore, the invention is embodied in a readily portable stove of simple construction and pleasing design, possessing various features of structural novelty, as will hereinafter appear.

In the accompanying drawings, Figure 1 is a perspective view of the stove, parts thereof being broken away to illustrate the internal arrangement. Fig. 2 is a vertical cross section on line 2--2 of Fig. 3, and Fig. 3 is a vertical longitudinal section of one end of the stove.

Referring to the drawings, 2 and 3 designate upright end-forming plates, each provided with the foot extensions 4, and each having near its upper end a hand-hole 5 by means of which the stove may be conveniently carried. The other essential parts of the stove, viz., the burner 6, the combustion chamber 7, and the perforated sheet-metal drum or hood 8, are arranged between and secured to the plates 2 and 3.

The tubular burner 6 extends longitudinally from end to end of the stove structure, plate 2 being provided with an opening 2' through which the burner is extended, and with a flange 6' on the burner engaging the outer surface of plate 2. This flanged end of the burner also carries the mixer 9 and socket 10, to which latter the gas main is connected. Projecting from the opposite extremity of the burner is the downwardly disposed slotted lug 11 to which bolt 12 is extended from plate 3, thereby securing the burner between the two end plates.

The combustion chamber 7 is of arch form, being disposed horizontally between plates 2 and 3, and with its ends closed by the latter. The chamber is fully open at its bottom, and its upwardly and inwardly curved sides 13 and its curved top portion 14 are perforated as shown. The combustion chamber is confined between lugs 15 and 15' on the inner surfaces of plates 2 and 3.

The combustion chamber is preferably formed in two longitudinal halves as shown, with lugs 16 projecting from the inner surfaces of the upper portions of the halves and meeting each other, and with cavities formed through the meeting edges of the lugs to receive bolts 17 which extend therethrough from plates 2 and 3. The two halves of the combustion chamber are tied together by three or more wires 18 extending through the chamber perforations and around its top portion, and with the parts thus united and with lugs 16 engaging each other the combustion chamber is quite as solid as though it were an integral structure. The bolts 17, together with the described mode of securing the burner results in connecting the parts together in a very substantial and permanent way.

The end plates 2 and 3 further serve to confine the perforated drum or hood 8 which is formed preferably of sheet-metal, the end plates being flanged as shown, and with occasional lugs 19 adjacent the flanges for confining the ends of the drum. The free edges of the drum are preferably overlapped beneath the burner at 20, though this last named feature is not essential.

The general shape of the combustion chamber is an important characteristic of the invention. The contracted sides operate to confine and deflect upwardly the flames and products of combustion, and so hold or retard the latter that practically all are consumed before they can escape from the chamber. The combustion chamber becomes highly heated, ordinarily attaining a cherry-red heat, and in the presence of such heat it will be understood that the products are very effectively disposed of. The perforated drum 8 fully incloses the combustion chamber, forming an effective guard, as well as an attractive finish for the stove without detracting from its heating efficiency. On the contrary, the perforated drum breaks up and disseminates the heat currents caus-

ing them to radiate from the stove in various directions.

By forming the combustion chamber in two halves as shown and described, the manufacture is greatly facilitated, and as the halves may be used interchangeably one mold suffices for both.

I claim:

1. In a gas stove, the combination of two end upright plates, a horizontal perforated combustion chamber, the chamber being open and widest at its bottom and contracted upwardly, the chamber ends formed with lugs, bolts fastening said lugs to the said upright plates; a perforated outer shell located between and confined by the said end plates, a burner at the base of the combustion chamber with means fastening the ends of the burner to the said upright plates, the burner and combustion chamber combining

to tie together the separable parts of the stove.

2. In a gas stove, the combination of two upright end plates, a perforated combustion chamber open at its bottom and secured at its ends to the end plates and constituting a tie for holding the parts assembled, a gas burner within the combustion chamber and secured to the end plates and constituting an additional tie between the latter, and a perforated drum spaced from the combustion chamber and held in place by the end plates.

In testimony whereof I affix my signature in presence of two witnesses.

JOHN M. TOBIAS.
